UNITED STATES PATENT OFFICE.

ALBERT N. SHEPLER, OF PERU, INDIANA.

RAIL TIE AND FASTENER.

1,158,319.

Specification of Letters Patent. Patented Oct. 26, 1915.

Application filed July 8, 1915. Serial No. 38,704.

To all whom it may concern:

Be it known that I, ALBERT N. SHEPLER, a citizen of the United States, residing at Peru, in the county of Miami and State of Indiana, have invented a new and useful 5 Rail Tie and Fastener, of which the following is a specification.

The present invention appertains to railroad cross ties, and aims to provide a metallic railroad tie provided with unique 10 means for fastening the rails thereon, the present tie being comparatively simple, and inexpensive, and being much more durable than the ordinary wooden tie.

With the foregoing and other objects in view which will appear as the description proceeds, the invention resides in the combination and arrangement of parts and in the details of construction hereinafter described and claimed, it being understood 20 that changes in the precise embodiment of the invention herein disclosed can be made within the scope of what is claimed, without departing from the spirit of the invention.

The invention is illustrated in the accompanying drawing, wherein:—

Figure 1 is a perspective view of the improved structure. Fig. 2 is an enlarged fragmental view illustrating a pair of the 30 rail fastening members in position to hold the rail upon the tie. Fig. 3 is a view similar to Fig. 2, illustrating the rail fastening members released and the rail removed.

In carrying out the invention there is provided a channel-shaped metallic tie 1 which may be laid upon the roadbed in the manner of an ordinary wooden tie, and which may be filled with rock or other ballast for holding it firmly in place. The rails 2 are supported upon the upstanding flanges of the tie 1.

Each flange of the tie is provided with means for holding each rail thereon, and to this end, two pairs of plates or bars 3, forming the rail holding members, are carried by each flange of the tie. The plates 3 of the opposite flanges of the tie are disposed opposite to one another, and the plates of each 50 pair are arranged at opposite sides of the respective rail. Bolts or cross rods 4 are engaged through the flanges of the tie 1 adjacent the upper edges of said flanges and adjacent the opposite sides of the respective

rails and the rods 4 serve to pivot the plates 55 3 to the flanges of the tie. The rods 4 pivot the plates 3 to the tie adjacent those ends of the plates 3 nearest the rails, and said ends of the plates 3 are provided with recesses or cut away portions 5 for accommodating the base flanges of the rails. Said recesses 5 provide the oblique edges 6, and projecting fingers 7, the edges 6 being adapted to bear against the edges of the base flanges of the rails for holding the rails in 65 proper position, while the fingers 7 are arranged to bear upon the base flanges for holding the rails upon the tie.

When the plates 3 are released, as seen in Fig. 3 they swing to pendant or vertical positions, with the fingers 7 projecting upwardly to readily receive the rails therebetween, and the rails in being seated upon the upper ends of the plates 3, will swing the plates 3 apart slightly. Then, by swinging the lower ends or long arms of the plates 3 apart and then upwardly, the edges 6 will bear against the side edges of the base flanges of the rails for moving the rails to proper position upon the tie, the base flanges 80 being clamped between the pairs of plates 3, and the fingers 7 then seat upon the base flanges for clamping the base flanges upon the tie. Then, when the plates 3 are swung properly to clamp the rails in place, bolts or 85 other retaining elements 8 are engaged through suitable apertures provided in the plates 3 and flanges of the tie. The bolts 8 are arranged adjacent those ends of the plates 3 opposite the fingers 7, whereby the 90 bolts 8 being engaged through the long arms of the plates or levers 3 will effectively hold the fingers 7 tightly upon the base flanges of the rails. The fingers 7 are carried by the short arms of the plates or levers 3, and the 95 plates are preferably disposed upon the inner sides of the flanges of the tie. The plates 3 are inclined or diverge downwardly, in which position the plates will effectively hold the rails. When the plates 3 are in depending position, the oblique edges 6 will be 100 swung above the flanges of the tie so as to converge downwardly to said edges of the tie flanges, whereby the base flange of the rail in seating upon the edges 6 will swing 105 the long arms of the plates 3 apart, to start the upward movement thereof.

When the bolts 8 are removed, the rails

can be readily detached from the tie, since the plates 3 will swing downwardly to release the rails.

Having thus described the invention, what is claimed as new is:—

In combination, a channel-shaped tie, a pair of rods engaged through the flanges thereof adjacent the upper edges thereof, two pairs of plates pivoted upon said rods adjacent the flanges and having short and long arms, the short arms having recesses to accommodate the base flange of a rail and providing oblique edges adapted to swing above said tie flanges when the long arms 15 are swung downwardly and also adapted to

engage the edges of the base flange of the rail when the long arms are swung upwardly, said recess also providing fingers to bear upon the base flanges, and means for individually securing said long arms to the 20 tie flanges when the long arms are swung upwardly.

In testimony that I claim the foregoing as my own, I have hereto affixed my signature in the presence of two witnesses.

ALBERT N. SHEPLER.
